DESIGN FOR A WEDDING RING

Monroe Sherman, New York, N. Y.

Application January 5, 1940, Serial No. 89,309

Term of patent 14 years

To all whom it may concern:

Be it known that I, Monroe Sherman, a citizen of the United States, resident of Queens, in the county of Queens, city and State of New York, have invented a new, original, and ornamental Design for Wedding Rings, of which the following is a specification, reference being had to the accompanying drawing, forming part thereof.

I claim:

The ornamental design for a wedding ring, substantially as shown.

MONROE SHERMAN.
